UNITED STATES PATENT OFFICE.

WILLIAM N. MOORE, OF POLLARD, ALABAMA.

LIQUID-SEALED JAR.

1,081,856.

Specification of Letters Patent.

Patented Dec. 16, 1913.

Application filed October 10, 1912. Serial No. 724,975.

To all whom it may concern:

Be it known that I, WILLIAM N. Moore, a citizen of the United States, residing at Pollard, in the county of Escambia and 5 State of Alabama, have invented certain new and useful Improvements in Liquid-Sealed Jars; and I do hereby declare the following to be a full, clear, and exact description of the invention, such as will enable others 10 skilled in the art to which it appertains to make and use the same.

This invention is a closure for jars or similar receptacles for preserving and conserving fruit, milk, wines and various other 15 articles of food, having for its object to provide an improved fluid seal between the jar and its cover or covers.

In preserving some articles of food it is essential that the jar shall be rendered airtight, protecting the contents thereof from 20 fermentation and contamination.

One object of the invention is to provide 25 convenient means for sealing the contents of the jar against contamination, which sealing means will permit of the escape of gases which may be formed within the jar, and at the same time preclude insects from gaining access to the contents of the jar.

With these ends in view, the invention 30 consists in providing the jar with a peripheral channel, the outer wall of which is on a lower plane than the mouth of the jar, and a plurality of covers, one of which is adapted to be seated within the peripheral channel 35 and contact with a fluid sealing substance within the channel.

Other objects and advantages of the device will become apparent from the following detailed description of the invention, 40 taken in connection with the drawings.

In the accompanying drawing, I have 45 illustrated one embodiment of the invention, but the construction shown therein is to be understood as illustrative, only, and not as defining the limits of the invention.

Figure 1 is a side elevation of the jar, Fig. 2 is a vertical sectional view through the jar, and Fig. 3 is an enlarged fragmentary view showing a portion of the central cover positioned within the peripheral channel.

The jar 5 may be composed of any suitable material, such as pottery, glass, and the like. 50 This jar is provided with a mouth 6, preferably of less diameter than the body of the jar, thereby forming a curved shoulder por-

tion 7 and an upstanding collar 8. The inner cover 9, having a depending flange 10, fits over the mouth of the jar. This inner cover 9 may be of any suitable material, and of any desired contour. The side walls 11 of the jar are preferably divided near the top thereof to form the curved shoulder portion 7 and an upstanding peripheral flange 12, thereby producing a peripheral channel 13 adjacent the mouth of the jar. This flange 12 is shown as curved outwardly from the side wall, and thence upwardly, until the edge of the flange is substantially concentric with the mouth of the jar. The upper edge 15 of this flange 12 is on a lower plane than the upper edge of the collar 8, forming the mouth of the jar, thereby precluding any liquid, which may be poured into the channel 13, from flowing into the mouth of the 20 jar. The base of the channel 13, which is in alinement with the side walls of the jar, is provided with means serving as a seat 14 for an intermediate cover 15, and in the drawings this seat is shown rounded, as in 25 Fig. 3. The outer cover 16 is adapted to engage, and fit over, the top of the outer flange 12, and this top 16 may be provided with a peripheral groove 17, or any other 30 suitable means for producing a tight joint 35 between the cover 16 and the flange 12.

The channel 13 is adapted to receive a suitable fluid for sealing the jar, and this fluid may be drawn off from the channel, when it is desired to gain access to the 40 contents of the jar, by opening a port 18, adapted to be closed by any suitable means. In the drawings, I have shown the port closed by a stopper 19, but it is obvious that any 45 other means may be employed.

The various covers may be provided with 50 any suitable means, as at 20, for handling the same. Furthermore, the jar 5 may be provided with suitable means for transporting it, such as the handle 21 pivoted to the 55 ears 22.

Should the cover 16 become broken, or accidentally displaced from position, or should the flange 12 become broken sufficient to permit the fluid, or a portion thereof, to escape from the channel 13, the covers 9 and 15 will serve to protect the contents of the jar. Even should the outer and intermediate covers 16, 15 become displaced from the jar, the inner cover 9 will serve to 100 close the jar.

In operation, the articles to be stored are

placed within the jar through the mouth 6, the cover 9 is placed in position over the mouth 6, then the intermediate cover 15 is positioned over the inner cover 9 until the 5 edge thereof engages the seat 14 of the channel 13. Any suitable fluid may be poured into the channel 13 to seal the jar, care being taken that port 18 is closed. The outer cover 16 may be placed in position 10 to engage the top of flange 12, thereby protecting the fluid from evaporation, as well as from dust and contamination with injurious substances. In storing fermenting substances within the jar 5, the gas may 15 be permitted to escape from the jar into the chambers between the inner and central covers, or between the central cover and the outer cover.

Having thus described my invention, 20 what I claim as new and desire to secure by Letters Patent, is:

- 25 1. In a device of the class described, a jar provided with a mouth, a flange concentric with the mouth producing a channel between the flange and mouth, a seat at the base of the channel, a cover adapted to engage the flange, another cover for the mouth of the jar, and an intermediate cover adapted to rest in the channel.
- 30 2. In a device of the class described, a jar provided with a mouth of less diameter than the body of the jar, a flange concentric with

the mouth of the jar, said flange being of greater diameter than the body of the jar, and on a lower plane than said mouth, and 35 a plurality of covers for the jar comprising an inner cover for the mouth of the jar, an intermediate cover adapted to rest on a seat in alinement with the walls of the jar, and an outer cover adapted to engage said flange. 40

3. In a device of the class described, a jar provided with a mouth of less diameter than the body of the jar, a flange concentric with the mouth of the jar of greater 45 diameter than the body of the jar, said flange forming a channel concentric with the mouth of the jar, a seat at the base of the channel, and a series of covers for said jar, one of said covers being provided with means for engaging the edge of the flange, 50 another of said covers adapted to fit over the mouth of the jar, and an intermediate cover adapted to be positioned to rest upon the seat within the channel and in alinement with the side wall of the jar, whereby when 55 fluid is placed within said channel, the intermediate cover will contact with the fluid.

In testimony whereof, I affix my signature, in presence of two witnesses.

WILLIAM N. MOORE.
